CLAIM

The ornamental design for a lamp, as shown and described.

DESCRIPTION

FIG. 1 is a perspective view of an embodiment a lamp; FIG. 2 is a front view of the lamp of FIG. 1; FIG. 3 is a front view of the lamp of FIG. 1 in an exploded state; FIG. 4 is a top view of the lamp of FIG. 1; and, FIG. 5 is a bottom view of the lamp of FIG. 1. A right side view, a left side view, and a rear view are omitted from the drawings as they are identical and duplicative to the front view shown in FIG. 2 and FIG. 3. The broken lines in the drawings depict portions of the lamp that form no part of the claimed design.
